(57) **CLAIM**

(21) Appl. No.: **29/242,351**

The ornamental design for a serial to parallel electrical transceiver, as shown and described.

(22) Filed: **Nov. 9, 2005**

DESCRIPTION

(51) **LOC (8) Cl. 13-03**

FIG. 1 is a top, front and right side perspective view of a serial to parallel electrical transceiver, showing my new design;

(52) **U.S. Cl. D13/147**

FIG. 2 is a top plan view thereof;

(58) **Field of Classification Search D13/123,**

FIG. 3 is a bottom plan view thereof;

D13/133, 146-147, 154, 184, 199; D14/356,

FIG. 4 is a right side elevational view thereof;

D14/432, 433, 435, 438; 439/350, 352, 357-358,

FIG. 5 is a left side elevational view thereof;

439/606-610, 660, 677, 680-682, 686, 936

FIG. 6 is a front elevational view thereof; and,

See application file for complete search history.

FIG. 7 is a rear elevational view thereof.

(56) **References Cited**

The broken line showing of the environment is for illustrative purposes only and forms no part of the claimed design.
